(Model.)

C. D. SMITH & R. H. THOMPSON.
PADLOCK.

No. 371,796.

Patented Oct. 18, 1887.

N. PETERS, Photo-Lithographer, Washington, D. C.

UNITED STATES PATENT OFFICE.

CHARLES D. SMITH AND ROBERT H. THOMPSON, OF HARTSELL'S, ALABAMA.

PADLOCK.

SPECIFICATION forming part of Letters Patent No. 371,796, dated October 18, 1887.

Application filed November 13, 1886. Serial No. 218,807. (Model.)

To all whom it may concern:

Be it known that we, CHARLES D. SMITH and ROBERT H. THOMPSON, of Hartsell's, in the county of Morgan and State of Alabama, have invented a new and Improved Padlock, of which the following is a full, clear, and exact description.

My invention relates to padlocks, and has for its object to provide a simple, strong, durable, and comparatively inexpensive combination-padlock which cannot be unlocked or opened by persons unacquainted with its interior mechanisms and the manner of operating them in proper order.

15 The invention consists in certain novel features of construction and combinations of parts of the lock, all as hereinafter fully described and claimed.

Reference is to be had to the accompanying drawings, forming a part of this specification, in which similar letters of reference indicate corresponding parts in all the figures.

Figure 1 is a front view of a padlock embodying my improvements, with the front plate removed and with different positions of the parts indicated in dotted lines. Fig. 2 is a cross-sectional view taken on the line $x-x$, Fig. 1. Fig. 3 is a view of the back or reverse side of the padlock, with parts indicated in dotted lines; and Figs. 4 and 5 are detail views of the ends of the lock, key, and hasp, respectively.

The back plate, A, of the lock shown has fixed to it a flange, a, to which the front plate, B, is held, and between lugs of the plates A B the hasp C is pivoted on a pin, c', so as to swing at its reduced end c through a hole or slot, a', in the flange a of the lock.

40 The bolt D of the lock is fitted to slide in guide-studs d d, fixed to the lock-case, and is shaped at the lower edge to be operated by a key-bit, and in its upper edge has the usual notches, d' d', into which the stud e on the tumbler E may enter after the latter is lifted by the key. The tumbler is pivoted at e' to the lock-case, and is acted on by one or two springs, e' e', to hold its stud into either notch of the bolt, the bolt and its tumbler being operated by the key in the usual manner.

50 In the plate A of the lock there is fitted a screw-bolt, F, which is adapted to a threaded

hole in the tumbler E, and may be screwed into the tumbler to prevent opening of the lock, or may be unscrewed to stand clear of the tumbler to allow it to be lifted and allow 55 the bolt to be thrown.

The end d' of the bolt D is adapted to enter a hole, c', made in the end c of the hasp C, and the other end, d', of the bolt is adapted to enter a hole, g, in the upper or outer end of a metal 60 bar G, fitted for endwise movement in the lock-case, and to which is fixed a pin, h, which passes through a slot, b, of the back plate, A, and has fixed to it, outside of said plate, a head or button, H. A spring, I, fixed at one 65 end to a stud, i, in the lock-case, acts normally by its other end against the end g' of the bar G to force said bar toward the top or hasp end of the lock to carry the hole g thereof above the end d' of the bolt D, and thus prevents 70 withdrawal of the bolt by the key until the bar G is drawn or slid backward by pressure on the button H to bring the hole g opposite the end of the bolt.

The key J (shown only in part in Fig. 4 75 and in dotted lines in Fig. 1) is to be entered into a hole, K, in the front plate, B, after an escutcheon or cover-plate, L, has been turned on its pivot l from over the key-hole, and the key engages a guide-pin, M, and is 80 fitted to turn past a ward, N, said pin and ward being fixed to the back plate, A, of the lock-case. The notch j in the key-bit, which allows the key to turn past the ward N, also serves as a wrench socket, allowing the use of the 85 key to set the parts of the lock to open it or prevent opening of it, as presently explained.

A dog or pawl, O, pivoted by a bolt, P, to the back plate, A, may be turned by engaging the head p of the bolt by the key-socket j, so 90 as to swing the dog either up to the position shown in full lines in Fig. 1, where it will be held by the engagement of the end of a spring, R, fixed to the lock-case, with a hole, o, in the dog; or the dog may be swung down to the position shown in dotted lines in Fig. 1, by turning the bolt P by the key, the spring R being shaped at its end r to allow it to engage the dog and permit escape of the dog from it automatically. A pin, S, fixed to the back plate, 100 A, forms a stop to the dog O, and has fixed to it a metal plate, s, which overlaps the end of

the upturned dog, and also the edge of the spring I, thus serving as a retainer to both the dog and the spring.

Another dog, T, is held to a bolt or pin, U, pivoted in the back plate, A, and having a head, u, outside the lock-case, and to which the key-socket j is adapted. This dog T is provided with a lug, t, adapted to enter a hole, c³, in the end c of the hasp C, and in which hole 10 said lug t is normally held, when the hasp is locked, by means of a spring, V, which is fastened at one end to the lock-case and bears by its other end, v, on the lower end or tail of the dog. The stud i, to which the spring I is 15 fixed, serves as a stop to prevent the spring V throwing the dog T too far in one direction, and a pin or lug, t', fixed to the back plate, A, prevents turning of the dog in the other direction any farther than is necessary to withdraw 20 the lug t thereof from the hasp.

When the padlock is fully locked, its parts will have the relative positions shown in full lines in Fig. 1 of the drawings. The screw F will then prevent operation of the tumbler and bolt E D, the dog O will prevent turning of 25 the key to the bolt, the bar G will prevent withdrawal of the bolt D from the hasp, and the dog T will prevent withdrawal of the end c of the hasp from the body of the lock.

To unlock the padlock, the screw F must be 30 unscrewed from the tumbler E, and the dog O must be swung over backward to the position shown in dotted lines in Fig. 1, which may be done by applying the key-wrench 35 socket j over the heads of the bolts F P, respectively. The key J may now be passed into the key-hole K and turned past the lowered dog O to the tumbler E, and when the bar G is slid backward by pressing back the 40 button H by the hand the bolt may be thrown back by the key, so its end d³ enters the hole g of said bar. The dog T must now be turned, by applying the key as a wrench to the bolt or pin U, to the position shown in dotted lines 45 in Fig. 1, which will withdraw the lug t from the hasp C, to allow the latter to be swung open.

It is obvious that the padlock cannot be 50 opened by any one not knowing its interior construction and how to operate the bolts or pins F P U and the button H at the outside of the lock, as above described; hence the lock is a very safe one, not likely to be picked by thieving persons. Furthermore, the lock 55 is very strong and may be made cheaply, and

is adapted for use where locks of this character may be advantageously employed.

Certain features of the invention herein described may be applied to flat-plate or door locks adapted for store or jail doors. 6c

Having thus described our invention, what we claim as new, and desire to secure by Letters Patent, is—

1. In a padlock, the combination, with the lock-case and bolt, of a movable bar, G, having a hole, g, to which the end of the bolt is adapted, and a spring, I, normally forcing the bolt to carry its hole g out of line with the end of the bolt, said bar having a pin, h, passed through a slot in the lock-case and adapted to 70 operate said bar, substantially as described, for the purposes set forth.

2. In a padlock, the combination, with the lock-case, of a dog, O, pivoted thereto and adapted to be thrown across the path of the 75 key, and said dog provided with a bolt, P, passing through the lock-case, a spring, R, adapted to hold the dog, and the stop S, limiting the movement of the dog, substantially as described, for the purposes set forth.

3. In a padlock, the combination, with the lock-case and a hasp, C, provided with a hole, c³, and a spring-pressed dog, T, having a bolt, U, passing through the lock-case, and a lug, t, adapted to enter said hole c³, of stops i t' in 85 the lock-case, substantially as shown and described.

4. A padlock constructed substantially as herein shown and described, and comprising a case, a pivoted hasp, C, a bolt, D, and 90 tumbler E, a bolt or pin, F, fitted to the case and adapted to a hole in the tumbler, a movable spring-pressed bar, G, having a hole, g, and a pin, h, passing through the lock-case, a dog, O, pivoted in the lock-case and adapted 95 to be thrown across the path of the entered key, and having a bolt, P, passing through the lock-case, a spring, R, and stop S for said dog O, and a spring-pressed dog, T, having a bolt, U, passing through the lock-case, and also 100 having a lug, t, adapted to enter a hole, c³, in the hasp C, and a stop, i, for the dog T, all arranged for operation, as and for the purposes set forth.
